(57) **CLAIM**

The ornamental design for a tiered jewelry stone setting, as shown and described.

DESCRIPTION

FIG. 1 is a perspective view of a tiered jewelry stone setting showing my new design;

FIG. 2 is a top plan view thereof;

FIG. 3 is a side elevation view thereof; with the opposite side being identical; and,

FIG. 4 is a sectional view thereof, taken along line 4—4 of FIG. 2.

The broken lines showing of a gem setting is for illustrative purposes only and forms no part of the claimed design.
